FISH LURE

Karl Nurmse, Svangsta, Sweden, assignor to Aktiebolaget
Urfabriken, Svangsta, Sweden

Filed Nov. 12, 1964, Ser. No. 82,574

Claims priority, application Sweden May 12, 1964

Term of patent 14 years

(Cl. D31—4)

FIGURE 1 is an elevation view of a fish lure showing my new design,

FIGURE 2 is a side view thereof (seen from the left of FIGURE 1),

FIGURE 3 is a perspective view thereof,

FIGURE 4 is a section on line 4—4 of FIGURE 1, and

FIGURE 5 is a section on line 5—5 of FIGURE 1.

The dominant features of my design reside in the portions in full lines.

I claim:

The ornamental design for a fish lure, as shown and described.
